Primary Examiner — Elizabeth Albert(74) *Attorney, Agent, or Firm* — Foley & Lardner LLP(57) **CLAIM**

We claim the ornamental design for a material punch, as shown and described.

DESCRIPTION

FIG. 1 is a perspective view of our claimed design. FIG. 2 is a front elevational view of the claimed design of FIG. 1. FIG. 3 is a rear elevational view of the claimed design of FIG. 1. FIG. 4 is a left side elevational view of the claimed design of FIG. 1. FIG. 5 is a right side elevational view of the claimed design of FIG. 1. FIG. 6 is a top plan view of the claimed design of FIG. 1; and, FIG. 7 is a bottom plan view of the claimed design of FIG. 1. The broken lines in the drawings are included for the purpose of showing portions that form no part of the claimed design.
